(57) **CLAIM**

The ornamental design for an ear plug having piston-like exterior, substantially as shown and described.

DESCRIPTION

FIG. 1 is a perspective view of a first embodiment of the invention.

FIG. 2 is another perspective view of the embodiment shown in FIG. 1.

FIG. 3 is a front view of the embodiment shown in FIG. 1.

FIG. 4 is a back view of the embodiment shown in FIG. 1.

FIG. 5 is a left view of the embodiment shown in FIG. 1.

FIG. 6 is a right view of the embodiment shown in FIG. 1.

FIG. 7 is a top view of the embodiment shown in FIG. 1.

FIG. 8 is a bottom view of the embodiment shown in FIG. 1.

FIG. 9 is a perspective view of a second embodiment of the invention.

FIG. 10 is another perspective view of the embodiment shown in FIG. 9.

FIG. 11 is a front view of the embodiment shown in FIG. 9.

FIG. 12 is a back view of the embodiment shown in FIG. 9.

FIG. 13 is a left view of the embodiment shown in FIG. 9.

FIG. 14 is a right view of the embodiment shown in FIG. 9.

FIG. 15 is a top view of the embodiment shown in FIG. 9; and,

FIG. 16 is a bottom view of the embodiment shown in FIG. 9.

The broken lines are directed to subject matter excluded from the claim.

1 Claim, 4 Drawing Sheets
